JOSEPH J. LOVELL, OF NEW YORK, N. Y., ASSIGNOR TO HIMSELF
AND GEORGE W. MILLAR, OF SAME PLACE.

Letters Patent No. 90,454; dated May 25, 1869.

IMPROVED EAVES-PROTECTOR.

The Schedule referred to in these Letters Patent and making part of the same.

To all whom it may concern:

Be it known that I, JOSEPH J. LOVELL, of New York, in the county of New York, and State of New York, have invented a new and improved Apparatus for Hoisting Hose; and I do hereby declare that the following is a full, clear, and exact description thereof, which will enable others skilled in the art to make and use the same, reference being had to the accompanying drawings, forming part of this specification.

This invention relates to an improved device to be used in hoisting hose over buildings, for throwing water upon fires, to facilitate the said hoisting, and protect the cornices and the hose.

It consists in an adjustable pulley-support, capable of attachment to any cornice, provided with a grooved pulley, over which the hose may be drawn with much less effort than when the same is drawn over the edge of the cornice, as is commonly done, and without damaging either the cornice or the hose, as now frequently happens.

Figure 1 represents a side elevation of my improvement, as applied to a cornice, and

Figure 2 represents a plan view of the same.

Similar letters of reference indicate corresponding parts.

A represents a frame, to be made of either wood or metal, composed of two parallel curved bars, united at B, and supporting a grooved pulley, C, near their curved ends.

Each bar is provided at the curved end with a slotted brace, D, having a pointed and curved end, E. These braces are secured to the sides of the bars A by set-screws F, and may be adjusted to any inclination from the point of connection.

The part B of the frame is provided with an eye-bolt, H, to which a rope may be applied to fasten to a chimney, or any other object for holding the device in its position.

In the case of buildings having no chimneys or other object on the top for fastening to, two of the said devices may be fastened together, the two being placed on opposite sides.

By the employment of this apparatus, applied to the cornice as represented in the drawing, and drawing the hose over the pulley, the hose may be hoisted upon the top of a building with very much less labor than when drawn up over the edge of the cornice, as is commonly practised at present, often seriously damaging them, especially when made of soft sheet-metal; also damaging the hose.

By reason of the adjustable braces, the apparatus may be applied to cornices of any form, without delay.

The curved ends of the bars A bear against the edge of the cornice, and permit the contact therewith of the pulley.

Having thus described my invention,

I claim as new, and desire to secure by Letters Patent—

An adjustable eaves-protector, for hoisting hose upon roofs, constructed substantially as herein described.

The above specification of my invention signed by me, this 13th day of January, 1869.

JOSEPH J. LOVELL.
